UNITED STATES PATENT OFFICE.

HARRY L. VAUGHAN, OF CHICAGO, ILLINOIS.

DESIGN FOR A POCKET BOTTLE-OPENER.

42,445.

Specification for Design.

Patented Apr. 30, 1912.

Application filed September 8, 1911. Serial No. 648,407. Term of patent 14 years.

To all whom it may concern:

Be it known that I, HARRY L. VAUGHAN, a citizen of the United States, residing at Chicago, in the county of Cook and State of Illinois, have invented a new, original, and ornamental Design for a Pocket Bottle-Opener, of which the following is a specification, reference being had to the accompanying drawing, forming part thereof.

The figure is a plan view of a bottle opener embodying my new design.

This invention relates to an improvement

in a new and useful design for a bottle cap remover of the character illustrated in the accompanying drawings, in which the figure is a plan view embodying my ornamental design.

I claim—

The ornamental design for a pocket bottle opener as shown.

HARRY L. VAUGHAN.
